UNITED STATES PATENT OFFICE.

ROLLIN M. HYDE, OF DETROIT, MICHIGAN, ASSIGNOR TO MCCORD RADIATOR & MFG. CO., OF DETROIT, MICHIGAN, A CORPORATION OF MAINE.

METAL TUBING.

Application filed May 11, 1928. Serial No. 277,067.

This invention relates to improvements in tubing and more particularly thin metal tubing, such as used for refrigerating and other heat or cold transferring purposes.

5 The main object of the invention is to provide a tube so constructed that it will be divided into two or more separate and distinct passages so that gas and liquids or different gases or different liquids may be 10 circulated through a single tube without mixing or interfering one with other.

Another object of the invention is to make the tube of several independently formed sections which when applied together to 15 complete the tube will provide the separate and distinct passages through the tube.

Another object of the invention is to provide means for holding the tube sections 20 tightly together and at the same time form extended radiating surfaces on the exterior of the completed tube.

The invention consists further in the materials hereinafter described and claimed.

In the accompanying drawings—

25 Fig. 1 is a side view of a spiral fin tube constructed in accordance with my invention;

Fig. 2 is a section through the tube on line 2—2 of Fig. 1;

30 Fig. 3 shows another form of the tube; and

Fig. 4 is a section taken on line 4—4 of Fig. 3.

In Figs. 1 and 2, the tube is made of two 35 half round seamless thin metal longitudinal sections 1, 2. The sections extend the full length of the tube and are substantially alike by being drawn over a die of the desired size and shape. After the sections are 40 made, they are placed together with their diametric flat walls 3, 3 in contact so as to form a complete round.

The two sections 1, 2 so assembled are 45 then run through a spiral fin applying machine and a relatively thin metal fin 4 is tightly wound on and about the outer circumference of the assembled sections in a spiral form. The fin 4, while or after being applied, is soldered to the sections and, 50 in addition to holding them tightly together, also provides the tube with extended radiating surfaces on the exterior of the tube. The finished tubes may be used straight or they may be bent in any shape desired.

55 With the tube made of two independ-

ently formed sections 1, 2, two separate and distinct longitudinal passages 5, 6 are provided in the tube for gas or liquids, the contacting diametric walls 3, 3 of the sections dividing the passages throughout the 60 entire length of the tube.

In Figs. 3 and 4, I have shown how a tube may be made of independently formed sections to provide three separate and distinct passages extending throughout the 65 length of the tube. As illustrated, the tube is made up of three segmental sections 7, 8, and 9, each being approximately one-third of the circle of the completed tube. These sections are preferably made alike by being 70 drawn over a die of the desired size and shape, and are then assembled with their radial flat walls 10, 10 in contact and meeting at the center of the tube to complete the 75 round.

The sections 7, 8, and 9 when so assembled are then run through a fin applying machine, and a metal fin 11 is tightly wound on and about the sections and soldered thereto to hold the sections together and complete 80 the tube with its extended radiating surface, as before. The sections 7 to 9 provide the three passages for the complete tube, said 85 passages being divided throughout the length of the tube by the contacting radial walls 10, 10 of the sections.

The number of passages required will depend on the number of sections of which the tube is formed, and I do not wish to limit my invention to any particular number of 90 passages, nor to any particular manner of making the passages in conjunction with a multiple passage tube with an extended radiating surface or surfaces on the exterior of the completed tube. Moreover, the fins 95 employed may be other than in spiral form. Individual flat fins could be used, or gang fins may be used with an assembly of my improved tubes, all without departing from the spirit and scope of my invention. 100

There are many places where my improved tubes may be used to advantage. In soda-water cabinets, where two temperatures are required, one for the ice-cream and the other for extracts and brick cream. In 105 direct expansion coils in connection with a brine for hold-over, the brine may be placed in one passage and sealed up, and the refrigerant circulated through the other passage. The tube may be used in making an 110

evaporator, using brine in one section of the tube. As a cooler for water for drinking fountains, the refrigerant may be circulated through one section of the tube and the drinking water through another. Other uses will be apparent to those skilled in the art to which my invention pertains.

I claim as my invention:

1. A tube consisting of separately formed longitudinal sections providing separate and distinct passages for the tube, and means for holding the sections together to complete the tube and to provide extended radiating surfaces on the exterior thereof.
2. A tube consisting of separately formed longitudinal sections providing separate and distinct passages for the tube, and fins about the sections to hold them together to complete the tube and to provide extended radiating surfaces therefor.
3. A tube consisting of separately formed longitudinal sections providing separate and distinct passages for the tube, and a fin spirally wound about the sections to hold them together to complete the tube and provide extended radiating surfaces therefor.
4. A circular tube consisting of separately formed longitudinal sections, each constituting a portion of the circle of the tube and providing a separate and distinct passage therefor, and fins about the sections to hold

them together to complete the tube and to provide extended radiating surfaces therefor.

5. A circular tube consisting of separately formed longitudinal sections, each constituting a portion of the circle of the tube and providing a separate and distinct passage therefor, and a spiral fin wound about the assembled sections for holding them together and to provide extended radiating surfaces therefor.

6. A circular tube consisting of two separately formed half round sections to provide separate and distinct passages for the tube, said sections being applied with their flat surfaces in contact to complete the circle of the tube, and fin means about the tube for holding its sections together and to provide extended radiating surfaces therefor.

7. A circular tube comprising a multiplicity of longitudinally extending segmental sections independently formed to provide separate and distinct passages for the tube, said sections being applied with their flat surfaces in contact to complete the circle of the tube, and a spiral fin wound about the outside of the tube for holding the sections together and to provide extended radiating surfaces therefor.

In testimony whereof I affix my signature.
ROLLIN M. HYDE.
